GARBAGE CAN HOLDER

Stephen Wargo, Streator, Ill.

Application November 5, 1945, Serial No. 626,666

2 Claims. (Cl. 248—146)

1

This invention relates to the official class of supports and more particularly garbage can supports.

The primary object of this invention resides in the provision of a support for garbage cans adapted to retain and lock the covers thereof so as to prevent dogs, cats and other roving animals from upsetting or removing the same and thereby spread the garbage over the adjacent area.

Another object of this invention resides in the provision of a support for a garbage can adapted to be adjusted to accommodate cans of different heights.

A further object of this invention resides in the particular construction of the standard.

A still further object of this invention resides in the particular construction of the garbage can supporting platform.

Aside from the aforesaid objects this invention resides in the particular construction of the stabilizing yoke for engaging the upper portion of garbage cans.

Among the many objects of this invention is the particular construction of the garbage can cover retaining arm.

One of the salient features of this invention resides in the particular combination of elements for removably supporting garbage cans and locking the covers thereon.

With these and other objects in view, this invention resides in certain novel features of construction and arrangement of elements to be hereinafter more particularly set forth in the specification, illustrated in the accompanying drawings and pointed out in the appended claims and, although this disclosure depicts my present conception of the invention, the right is reserved to resort to such departures therefrom as come within the spirit of the invention.

In the accompanying drawings forming a part of this application;

Fig. 1 is a side view of the garbage can support.
Fig. 2 is a plan view thereof.

Fig. 3 is a front view of the garbage can support.

Fig. 4 is a perspective view of the standard.

Fig. 5 is a perspective view of the platform.

Fig. 6 is a perspective view of the stabilizing yoke.

Fig. 7 is a perspective view of the arm for locking the cover on the garbage can.

In the present illustration of this invention, the numeral 5 designates, in general, a garbage can support adapted to be disposed in the back yards of residences or other elected places from which

garbage is collected and preferably consists of an angle iron standard 6, a substantially circular platform 7 of skeleton construction, a substantially semi-circular yoke 8 for retaining a garbage can in upright position on the platform, and an arm 9 swingably secured to the standard for horizontal movement over the garbage can cover.

The standard 6 consists of upper and lower sections 10 and 11 connected by a similarly shaped plate 12 having elongated vertical slots 13 therein to accommodate bolts 13' passing through apertures 14 in said sections to retain them in adjustable relation through the instrumentality of nuts 15 or the like screwed thereon.

15 Welded or otherwise secured to the lower section 10 and extending at right angles therefrom is a platform 7 which consists of a strap of metal having its inner portion bent at right angles as indicated by the numeral 16 to seat in the lower section 6 for secure welding thereto with its outer portion or arms 17 indicated by the numeral 18 continuing from the aforesaid right angle portions thereof on arcuate lines to provide a substantially circular flange above the garbage can 20 supporting straps 19 welded or otherwise secured to the lower edges thereof in spaced relation to one another. Said arms 17 have their outer or free ends spaced as indicated by the numeral 20 to permit grasping of the lower outer edge of a 25 garbage can to lift it off the straps 19 a sufficient distance to clear the upper edges of the arms.

The aforesaid yoke 8 has its inner portion 21 shaped similarly to the inner end of the platform for seating the same in the upper section and 35 welding it thereto while its outer portions 22 are of arcuate shape with their free ends bent outwardly as indicated by the numeral 23 to permit the upper portion of a garbage can to rest therebetween so as to hold it erect on the platform and 40 yet permit easily removal therefrom.

Secured within the angular portion of the yoke, as by welding or otherwise, is an elongated sleeve 23' having its bore 24 preferably disposed in a perpendicular plane to accommodate a trunnion 45 25 formed on the inner end of an arm 26 which is adapted to swing on a horizontal plane closely over or in contact with the cover of a garbage can seated on the platform so as to prevent dogs and the like from removing the same or dislodging the garbage can from the platform. Said trunnion is provided with a flange 27 adapted to rest on the upper end of the sleeve and, in order to retain it in operative position in the sleeve, a cotter-pin 28 is inserted in an aperture 29 adjacent the lower end thereof.

Although the lower end of the standard is sharpened as indicated by the numeral 30 for driving the same into the ground, it is within the purview of this invention to fix the standard to a support with any well known means capable of supporting the same for carrying out the functions of the invention with the elements recited.

With this invention fully set forth, it is manifest that means are provided for both supporting a garbage can in secure position above the ground and retaining its cover thereon against removal by dogs, cats and other roaming animals and, through the particular assemblage of cooperative elements, the support can be manufactured cheaply and sold at a nominal price.

Having thus described my invention what I claim and desire to protect by Letters Patent is:

1. In a garbage can support comprising a standard of angle iron configuration, a platform having its inner end portion of a shape similar to that of the standard and those portions extending therefrom of arcuate configuration with their free ends terminating in spaced relation to one another, means rigidly securing the platform to the standard with its angular portion seated in the angular portion of the standard and at right angles thereto, a substantially semi-circular yoke having its inner portion of a shape similar to that of the standard and those portions extending therefrom of arcuate configuration with their free ends bent outwardly on a line passing approximately through the center of a circle upon which the outer portions of the yoke are drawn, a sleeve secured within the angular portion of the yoke and having its bore disposed in a per-

pendicular plane, a garbage can cover locking arm, and means securing the arm to the sleeve for swinging movement on a horizontal plane over the cover of a garbage can seated on the base.

- 5 2. In a garbage can support, comprising a standard consisting of aligned upper and lower sections of angle iron, an angle iron plate having elongated slots therein connecting the aforesaid upper and lower sections of the standard, bolts passing through the opposed end portions of the sections and slots in the plate, nuts on the ends of the bolts, a substantially circular platform including can supporting straps secured to the lower section of the standard and disposed horizontally at right angles thereto, a substantially semi-circular yoke secured to the upper section of the standard and disposed horizontally at right angles thereto above the platform with its free ends bent outwardly in opposite directions, a sleeve secured within the yoke at its inner end with the opposite ends thereof terminating above and below the upper and lower edges thereof and its bore disposed in a perpendicular plane, a garbage can cover locking arm, a trunnion formed on the inner end of the arm at right angles thereto to dispose in the bore of the sleeve for swingably supporting the arm on a horizontal plane in close relation to the cover of a garbage can seated on the platform, a collar formed on the trunnion and resting on the upper surface of the sleeve, and fastening means rotatably securing the trunnion within the bore of the sleeve.

20 25 30 STEPHEN WARGO.
